SIMPLIFIED LOOSE-LEAF BINDER

Filed Nov. 15, 1945

UNITED STATES PATENT OFFICE

2,498,584

SIMPLIFIED LOOSE-LEAF BINDER

Samuel Segal, New York, N. Y., assigner to Wilson-Jones Co., Chicago, Ill., a corporation of Massachusetts

Application November 15, 1945, Serial No. 628,679

1 Claim. (Cl. 129—24)

1

The subject matter of this invention is a loose leaf binder wherein a stack of sheets of paper may be quickly threaded on or removed from a ring section carrier adapted to be rotatably shifted relative to a reinforcing strap appropriately anchored to one panel of a flexible cover for the stack. The dominant object of the invention is realized in the provision of spaced bearing means on the strap for rotatably guiding the axle of the ring section carrier against the resistance offered by a medially arranged part of the strap against cam means projecting from the axle whereby the ring section carrier may be held in its fully closed position against accidental opening and against accidental closing when in a partly or fully opened position. The invention has as a further object the provision of a simplified loose leaf binder wherein the ring section carrier on closing thereof on passing its dead center is automatically rotated to its full closing position and on opening thereof on passing its dead center is automatically rotated to its full open position. Other important objects and functional and structural advantages will appear from the following detailed description taken with the accompanying drawings wherein:

Fig. 1 is a perspective view of a portion of the loose leaf binder according to my invention, removably interlocking with a swingable panel or top cover for a stack of papers.

Fig. 2 is a perspective view of the loose leaf binder showing the swingable panel raised and illustrating the binder closed or locking the stack papers.

Fig. 3 is a longitudinal sectional view on the line 3—3 of Fig. 1.

Fig. 4 is a fragmentary plan view illustrating the ring section carrier in its normal closed position.

Fig. 5 is a view similar to Fig. 4 showing the ring section carrier fully opened.

Fig. 6 is a vertical sectional view on the line 6—6 of Fig. 4, exhibiting the ring section carrier in a closed position and held against opening by a reinforcing and resilient strap.

Fig. 7 is an enlarged sectional view on the line 7—7 of Fig. 6.

Fig. 8 is a view similar to Fig. 6 showing the full deflection of the strap when the ring section carrier is partly opened.

Fig. 9 is an enlarged sectional view on the line 9—9 of Fig. 8, illustrating the ring section carrier at dead center.

Fig. 10 is a view similar to Fig. 8, illustrating

2

the deflection of the strap when the ring section carrier is fully opened.

Fig. 11 is a transverse enlarged sectional view on the line 11—11 of Fig. 10.

Fig. 12 is a perspective view showing one manner of opening the rotatable ring section carrier and

Fig. 13 is an enlarged sectional view on the line 13—13 of Fig. 4.

10 Illustrative of the embodiment disclosed, the loose leaf binder generally denoted LL is interposed between upper and lower panels 10 and 11 integrally merged with the arcuately shaped end 12 whereby the upper panel may be swung towards or away from the lower panel. Panels 10 and 11 and their integral connection 12 may be considered as a one piece flexible cover herein designated C.

Fixedly fastened to the upper part of panel or support 11 is a relatively thin, slightly resilient sheet metal strap 13 which is disposed flatwise against the top surface of panel 11 and has its ends 14 bent under and secured tightly against outside face of the panel 11. By this arrangement, the side margins of the panel 11 are tightly and firmly retained by the ends of the strap 13 and the latter may be considered as reinforcing means for the panel 11.

Integral with strap 13 are the spaced bearings 15 which rotatably confine the rod or axle 16 having a plurality of half ring sections or arcuately shaped hooks 17. The axle is integral with the end hooks 17 and together for purposes of specification these parts may be said to characterize a ring section carrier or one piece stay adapted to be bodily rotated or rocked relative to the spaced bearings 15.

Depending from and integral with axle rod 16 is the tapered tooth or cam 18 which normally 40 stresses and abuts the medial portion 19 of the strap 13, causing this portion 19 to be deflected downwardly to define an arcuately distended membrane between the bearings 15. This membrane reacts on the tooth or tapered and relatively narrow lug 18 whereby the axle is held in a set position against accidental rotation. Thus when the end hooks 17 are closed as indicated in Figs. 3, 4, and 7, they are so held by the reactive force imparted by the deflected membrane 19 on the cam 18.

On opening of the hooks 17 either of the latter may be grasped by the operator and shifted towards the operator and above the strap 13. Consequently the axle 16 is rotated and the cam 55 or tapered projection 18 further stresses and fur-

ther deflects the membrane portion 19 of the resilient strap 13 until the hooks 17 are about half opened at which time the cam may be said to be at its dead center (Fig. 9).

Having passed the dead center, the relatively narrow and tapered lug or cam 18 reduces its intensity on the membrane portion or centrally arranged resilient portion 19 permitting the latter to retract automatically but not completely in that even when the hooks 17 are fully opened the membrane portion 19 is under slight deflection by the cam 18, hence holding the rod or axle in a set position against accidental rotation to cause closing of the hooks. On moving to the full opened relation, the lower portions 20 of the hooks 17 abut the strap 13 (Fig. 11), hence precluding further rotational opening of the sectional ring carrier and the latter at this time may be said to be fully opened even though at this time the strap is under slight tension as previously pointed out, thus holding the ring section carrier against accidental closing.

With the hook or ring sections 17 partly or fully opened, loose leaf sheets 21 of a stack of papers S may be threaded on the hooks 17, that is, the free terminals of the hooks may be quickly projected through superimposed and alined slots as 22 in the perforated sheets 21 of the stack and thereafter the operator applies finger pressure to the exposed portions of the hooks to urge the latter to swing over the posterior margin 23 of the stack to their closed position adjacent the panel 11 (Figs. 3 and 7), that is, the terminals of the hooks in their fully closed relation project beyond but contiguous to the posterior longitudinal edge of the strap and even below the upper surface of the latter.

On shifting of the hooks 17 to their closed position, cam 18 accentuates the deflection of the membrane 19 until the dead center is reached and thereafter the deflection decreases but even so the hooks automatically fully close to straddle and lock the marginal portion 23 of the stack. It is thus apparent that by actuating the hooks, the axle 16 is rotated or rocked to permit opening or closing of the hooks at which time the compressor or strap 13 is always under tension or deflection so that if desired the hooks may be retained in a partly opened relation or in a fully opened position, the partial opened relation being retained when the tapered tooth or cam 18 reaches its dead center (Figs. 8 and 9) at which time tooth 18 stresses the intervening or medially disposed membrane 19 to its greatest deflection and hence the maximum thrust by the membrane is applied to the nose or base of the tooth 18, thereby frictionally braking the latter at the dead center whereby the stay characterized by the axle 16 and the spaced hooks 17 are held in a partially opened position.

Having properly locked the stack S on closing of the hooks 17, the upper panel 10 of the cover C is swung down against the stack whereby the upper portion of the hooks or ring sections 17 slightly pass through the spaced slots 24 in the upper panel 10 to preclude bulkiness and thus providing a compact organization. Moreover, by this arrangement, the upper panel 10 is properly alined in that the hooks 17 on being received by the spaced slots 24 more positively position the upper panel relative to the lowel panel.

Where the upper panel 10 is swung away from the stack, the latter if desired may be bodily grasped (Fig. 12) and pulled towards the oper-

ator. By this action hooks 17 are quickly opened. Thus a sheet of stack S or the latter may be quickly removed and another sheet or stack readily substituted. Subsequently the hooks are manually actuated to shift the cam 18 through its dead center and thereafter the reactive force imparted by the membrane 19 automatically retracts the hooks to their closing position.

Various changes may be made in details of construction and arrangement of parts without departing from the spirit of the invention or sacrificing any of the advantages thereof inherent therein.

I claim:

15 A loose leaf binder for a stack of sheet material with alined openings and adapted to be removably placed on a panel, a strap disposed widthwise of and having means for securing thereof to said panel and having spaced bearings integral with 20 and extending from anterior portions of said strap and embodying a medially arranged resilient portion disposed intermediate of said bearings, a one piece stay comprising an axle rotatably guided by said bearings and spaced hooks disposed substantially normal to and integral with said axle and adapted to be removably threaded into said openings upon rotation of said axle in one direction for arranging the free terminals of said hooks to fully close said stay, said terminals in the fully closed relation of said stay extending beyond but contiguous to the posterior longitudinal edge of said strap and projecting below the upper surface of the latter and said hooks being adapted to be removed from said 25 openings for fully opening of said stay upon rotation of said axle in a counter direction, and a tapered and relatively narrow lug arranged substantially centrally of, integral with and carried by said axle above said resilient portion for tensioning and deflecting the latter towards said panel in the fully opened relation of said stay and for progressively tensioning and further flexing said resilient portion on rotation of said stay 30 relative to said strap after said stay has been shifted from its fully opened relation towards its fully closed relation during which time said lug passes its dead center after which said tensioning and flexing of said resilient portion progressively decreases whereby said resilient portion automatically actuates said lug to rotate said axle to shift said stay from its partial open relation at said dead center to its fully closed relation, said lug and resilient portion frictionally engaging to hold said stay in a partial opened relation 35 thereof when said lug is at said dead center.

SAMUEL SEGAL.
